COCKTAIL SHAKER

Samuel Cominsky, Trenton, N. J., assignor to
Efcelite Corporation, Trenton, N. J., a corpora-
tion of New York

Application May 4, 1934, Serial No. 723,826

5 Claims. (Cl. 215—83)

My present invention relates to shakers for cocktails and other liquid refreshments.

An object of the invention is the embodiment of the shaker in body and closure cap of porcelain or other vitreous material and the provision of closure means inclusive of the closure cap for effectively sealing the mouth of the body of the shaker. The closure means preferably includes resilient means for the cap member, such resilient means and the cap member being mounted within the closure means as a unit.

In the preferred forms of the invention, the closure means includes an outer casing member of metal, which may be plated or the metal itself provide for artistic appearance. In such preferred forms of the invention, the closure means is secured to the mouth of the body of the shaker by the provision of interrupted cam ridges located adjacent the mouth of the body of the shaker, with which cam ridges cooperate a corresponding number of lugs carried by the casing member of the closure means, such lugs serving also to retain the cap member within the casing of the closure means when the closure means is removed from the body of the shaker.

Further features and objects of the invention will be more fully understood from the following detail description and the accompanying drawing, in which

Fig. 1 is a perspective view of a preferred form of shaker embodying my invention.

Fig. 2 is a detail vertical sectional elevation view on line 2—2 of Fig. 1, on an enlarged scale.

Fig. 3 is a top plan view of the body of the shaker, the closure means being removed.

Fig. 4 is a bottom plan view of the closure means.

Fig. 5 is a detail elevational view of the top portion of the body of the shaker.

Referring to the drawing which illustrates a preferred type of my invention, the body 10 of the shaker proper is preferably of porcelain or other suitable vitreous material. Its surface contour and its body configuration may be varied and ornamented as desired. As typical ornamentation I have indicated flutings, see 10a, Fig. 1.

The body of the shaker may be provided with an inner, perforated lip 11, which optionally may be integral with the body of the shaker. Such lip 11 extends but partially interiorly of the shaker, to afford a clearance, see 12, Fig. 2, for charging the ingredients into the shaker.

Such preferred forms of the invention includes adjacent the lip 13 of the body of the shaker,

a set of interrupted cam ridges 14, 14, 14, in this instance three in number, and intermediate such cam ridges there is thus provided a corresponding number of clear spaces 15, 15, 15, the purposes of which will appear more fully herein-after.

The closure means embodies a cap member 16 desirably of porcelain or analogous vitreous material, recessed annularly, see 17, to receive the lip portion 13 of the body 10 of the shaker, the face portion 17a of such annular recess 17 being suitably contoured relative to the edge face of the lip 13 to effect a sealing engagement therewith when the closure member is brought to sealing position.

To effect sealing engagement of the cap member 16 relative to the mouth of the shaker, I further provide suitable resilient means and cooperating parts associated with the cap member 16, such cooperating parts including a disk member 18, which is circularly depressed at its central portion 18a, the cap member 16 being provided with a central recess 16a; within such recess 16a is disposed an expansile coil spring 19, the upper end of which is positioned about 25 the stated central depressed portion 18a, of the said disk member 18, the aforesaid being housed and unitarily assembled within the outer casing member 20.

The unit assembly is preferably had by the provision of lugs 21, in this instance three in number, see Fig. 4, connected to, and preferably integral with, the lower edge of the casing member 20, such lugs 21 serving the dual purposes of retaining the cap member 16, namely by engagement of its outer annular portion 16b with the lugs 21, and the further function of coaction by the stated lugs 21, with the cam ridges 14 for effecting sealing engagement of the cap member 16 with the body of the shaker. Specifically, the closure means is placed above the mouth of the shaker to locate the respective lugs 21 at the clear spaces 15, and the closure means is turned by grasping the outer casing member 20, in this instance in right-hand screw direction, whereby the respective lugs 21 engage the lower edge faces of the cam ridges 14 and the cap member 16 is brought into uniform resilient sealing engagement at its annular face 17a with the edge face of the lip 13, the pitch of the cam ridges 14 being substantially uniform and affording through the respective lugs 21 the compression of the spring 19, thus rendering possible and effective the use of vitreous or like material for the shaker proper and the cap member of the closure means.

Such assembly of my closure means affords the further provision of a recipe dial, specifically in the form of a circular disk 22, on the upper face of which are imprinted or otherwise arranged in 5 sector relation, see 22a, Fig. 1, directions for and/or the ingredients of various cocktail recipes, and/or other liquid refreshments, each recipe 22a being visible through a cut-out or window 20a in the upper portion of the casing member 20; the 10 recipe dial member 22 may be rotated in any suitable manner, as by means of a button 23 suitably secured to the disk member 22, as by means of a stud 24.

Preferably, the recipes are impressed upon the 15 face of the recipe dial in water- and liquid-proof ink, or by etching, and the like, to be immune from defacing by contact with water and with the ingredients of the liquid.

My invention, particularly its closure means, 20 enables the parts to be effectually cleansed, in which operation the recipe visible window of the casing member of the closure means affords venting and consequent drying of the cleansing fluid, and further enhanced by the relatively small dimension of the inturned lugs and the clearance 25 between the cylindrical rim of the casing member and the displacingly therein enclosed cap member; in the furtherance of such purpose, the disk 18 is perforated, see 18b.

30 It is further pointed out that the spaced ridges 14, 14, 14, may not be of cam relationship, that is to say, their effective faces may extend substantially parallel to the edge face of the lip 13, the resilient mounting of the cap member 16 relative 35 to the clamping lugs 21, affording the sealing of the cap member relative to the mouth of the shaker body independently of any cam relation of the ridges 14.

Whereas I have described my invention by reference to specific forms thereof, it will be understood that many changes and modifications may be made without departing from the spirit of the invention.

I claim:

45 1. A shaker for cocktails and other liquid refreshments, comprising a shaker body of vitreous or other fragile material, said shaker body being provided with locking means adjacent its mouth, and closure means for the mouth of the shaker body, said closure means including a cap member of vitreous or other fragile material fitting within and around the top of said shaker body, said closure means further including a casing member displacingly enclosing said cap member, resilient means interposed between said cap member and said casing member and locking means carried by said closure means cooperating with said locking means of said shaker body, said locking means carried by said closure means including peripherally spaced elements respectively cooperating with said locking means of the shaker body and loosely engaging said cap member peripherally and at its lower edge, whereby the cap member and its interposed resilient means are retained as a unit within the casing member of the closure means upon removal of the closure means from the shaker body.

70 2. A shaker for cocktails and other liquid refreshments, comprising a shaker body of vitreous or other fragile material, said shaker body being provided with cam locking means adjacent its mouth, and closure means for the mouth of the shaker body, said closure means including a cap member of vitreous or other fragile material fitting within and around the top of said shaker

body, said closure means further including a casing member displacingly enclosing said cap member, resilient means interposed between said cap member and said casing member and cam locking means carried by said closure means cooperating with said cam locking means of said shaker body, said locking means carried by said closure means including peripherally spaced elements respectively cooperating with said locking means of the shaker body and loosely engaging said cap member peripherally and at its lower edge, whereby the cap member and its interposed resilient means are retained as a unit within the casing member of the closure means upon removal of the closure means from the shaker body.

15 3. A shaker for cocktails and other liquid refreshments, comprising a shaker body of vitreous or other fragile material, said shaker body being provided with a set of relatively spaced cam locking elements disposed adjacent the mouth 20 of the shaker body, said shaker body being provided with locking means adjacent its mouth, and closure means for the mouth of the shaker body, said closure means including a cap member of vitreous or other fragile material fitting within and around the top of said shaker body, said closure means further including a casing member displacingly enclosing said cap member, resilient means interposed between said cap member and said casing member and a set of correspondingly spaced locking elements carried by said closure means cooperating with said set of cam locking elements of said shaker body, said locking means carried by said closure means including peripherally spaced elements respectively 35 cooperating with said locking means of the shaker body and loosely engaging said cap member peripherally and at its lower edge, whereby the cap member and its interposed resilient means are retained as a unit within the casing 40 member of the closure means upon removal of the closure means from the shaker body.

4. A shaker for cocktails and other liquid refreshments, comprising a shaker body of vitreous or other fragile material, said shaker body being 45 provided with a set of cam locking elements respectively spaced from one another by clear spaces peripherally of and adjacent its mouth, and closure means for the mouth of the shaker body, said closure means including a cap member of vitreous or other fragile material fitting within and around the top of said shaker body, said closure means further including a casing member displacingly enclosing said cap member, resilient means interposed between said cap 50 member and said casing member and a set of lugs carried by said casing member cooperating with said set of cam locking elements, said locking lugs being dimensioned to pass through said clear spaces in the stages of moving said closure means to and from its closing position, said locking means carried by said closure means including peripherally spaced elements respectively cooperating with said locking means of the shaker body and loosely engaging said cap member peripherally and at its lower edge, whereby the cap member and its interposed resilient means are 55 retained as a unit within the casing member of the closure means upon removal of the closure means from the shaker body.

70 5. A shaker for cocktails and other liquid refreshments, comprising a shaker body of vitreous or other fragile material, said shaker body being provided with a set of cam locking elements respectively spaced from one another by clear 75

spaces peripherally of and adjacent its mouth, and closure means for the mouth of the shaker body, said closure means including a cap member of vitreous or other fragile material fitting within and around the top of said shaker body, said closure means further including a casing member displacingly enclosing said cap member, resilient means interposed between said cap member and said casing member and a set of peripherally spaced lugs carried by and inturned relative to said casing member cooperating with said set of cam locking elements, said inturned locking lugs being dimensioned to pass through

said clear spaces in the stages of moving said closure means to and from its closing position, said locking means carried by said closure means including peripherally spaced elements respectively cooperating with said locking means of the shaker body and loosely engaging said cap member peripherally and at its lower edge, whereby the cap member and its interposed resilient means are retained as a unit within the casing member of the closure means upon removal of the closure means from the shaker body.

SAMUEL COMINSKY.
